UNITED STATES PATENT OFFICE.

SIDNEY F. MOORE, OF DELAWARE TOWNSHIP, HANCOCK COUNTY, OHIO.

STOCK-FEEDING APPARATUS.

No. 907,264.

Specification of Letters Patent.

Patented Dec. 22, 1908.

Application filed April 7, 1908. Serial No. 425,671.

To all whom it may concern.

Be it known that I, SIDNEY F. MOORE, a citizen of the United States, residing in Delaware township, in the county of Hancock 5 and State of Ohio, have invented certain new and useful Improvements in Stock-Feeding Apparatus, of which the following is a specification.

This invention relates to apparatus for feeding stock, and more particularly to sheep-racks.

The object of the invention is to provide a convenient and practical apparatus of this kind, and also one which is so constructed 15 and operated that each animal will receive a proper share of the feed; and to this end the invention consists in a novel construction and arrangement of parts to be hereinafter described and claimed.

20 In the accompanying drawing, Figure 1 is an elevation of the invention. Fig. 2 is a transverse sectional view. Fig. 3 is a central longitudinal section. Fig. 4 is a sectional detail showing the hinge construction 25 hereinafter referred to.

The rack is double and comprises two rows of suitably spaced posts 9 embedded in the ground or otherwise suitably supported, and connected by longitudinal bars 10 to 30 which the vertical rack-bars or parting strips 11 are secured. The posts of one row are also connected to the posts of the other row by stringers 12 which support the flooring 13 and feed-troughs 14. The animals feed from 35 the outside through the spaces between the bars 11, the feed-troughs 14 being located behind the bars, with a space between the troughs to afford a passage-way for the attendant when filling the same. The rack 40 herein described is located under a shed or other suitable shelter.

Each feed-trough has a cover 15 which is hinged in such a manner that it may be swung open from either the front or the rear 45 side of the trough, for a purpose to be hereinafter described. This hinge connection comprises cross rods 16 and 17, respectively, the former being connected at one end to the front side of the trough, and at the other end 50 to the rear edge of the cover. The rod 17 is connected at one end to the rear side of the trough and at the other end to the front edge of the cover. By means of this hinge connection the cover may be swung open from 55 either side. When the cover is swung open from its front side, the rear ends of the rods

serve as a hinge, and when the cover is swung open from its rear side, the front ends of the rods serve as a hinge. The connection between the cover and the trough, and the 60 rods, is made by means of plates 18 secured to the cover and the trough, and having eyes 19 into which enter hooks 20 at the ends of the rods. The top edges of the trough are suitably grooved as indicated at 21 to receive 65 the rods when the cover is on. The cover is in sections, the number of sections employed depending on the length of the trough, and a hinge connection as herein described is provided for each cover-section. 70

The object of the hinge connection herein described is to provide means for shutting out the animals from the troughs when the latter are being filled. Upon opening the cover from the front of the trough and 75 swinging it rearwardly, it will extend along the bars 11 behind the same as shown by dotted lines in Fig. 2, in which position of the cover the animals are barred from the trough. When the cover is swung the other way as 80 shown by dotted lines in Fig. 2, the barrier is removed, and the animals can then reach the feed-troughs through the spaces between the bars 11.

For operating the covers as herein described the following means are employed: On cross-bars 22 secured to the rafters of the shed are mounted a series of pulleys which are arranged in pairs or groups of two, one of the members of which is designated by the 90 reference numeral 23, and the other by the reference numeral 24. From the posts 9 project brackets 25 and 26, the former carrying a guide-pulley 27, and the latter a guide-pulley 28 at its outer end. The bracket 26 95 is let into the post 9 on one side thereof, and on the opposite side of the post is a recess in which is mounted a pulley 29. The number of pulleys employed depends on the number of cover-sections, as many sets of pulleys 100 herein described being used as there are cover-sections. A system of pulleys as herein described is employed for the feed-troughs on both sides of the racks.

On one of the end walls of the shed is rotatably mounted, in a suitable bracket 30, an oval-shaped cam 31 fitted with a hand-lever 32 for turning the same on its pivot. Around the periphery of the cam pass ropes 33 and 34, respectively, which also travel over the 110 pulleys heretofore referred to as will be presently described. The ropes are fastened to

the cam by a suitable clamping device 35 so that when the cam is rotated one end of the rope is given a pull and the other end is slackened. In the periphery of the cam are 5 grooves to receive the ropes and prevent slipping thereof.

One end of the rope 33 passes over the pulleys 23, and carries at suitable intervals branch ropes 36 which also travel over said 10 pulleys and pass down to and under the pulleys 27, thence over the pulleys 28, and then to the rear end of the cover-sections to which they are connected. The other end of the rope 33 passes over the pulleys 24 and also 15 carries at suitable intervals branch ropes 37 which pass down to and under the pulleys 29, and thence to the front end of the cover-sections to which they are made fast. The two 20 ends of the rope 34, are connected to the cover-sections of the feed-trough on the other side of the rack, the arrangement being the same as herein described, and they are brought across from said side to the cam 31 by guide-pulleys 38.

25 By means of the rope gearing herein described, when the cam is rotated in one direction by means of the hand-lever, the cover-sections swing open from the front sides of the troughs to shut out the animals as herein 30 described, and when the cam is rotated in the other direction, the cover-sections swing open from the rear sides of the troughs whereupon the bars 11 are uncovered and the animals have access to the troughs.

35 As the covers of both troughs are operated from one cam, they operate simultaneously. Ropes may be used throughout for operating the covers as herein described, but being liable to be nibbled by the sheep, or by mice, 40 rats, etc., I use rubber belts from the troughs to the pulleys 27 and 29, then wire to the pieces of ropes which play through the pulleys 23 and 24, and wire for the main lines above except where it comes down to the cam, and to the extreme end of the trough. 45 Additional means for shutting out the animals are also provided, said means comprising boards 39 mounted to slide up and down between the posts 9 in guide-ways formed

50 by strips 39* nailed to the post and projecting from opposite sides thereof. In these strips are slots through which the branch ropes 37 pass to the pulleys 29. The slides are operated by ropes 40 connected thereto, and fastened at one end to a drum 41 rotatably mounted in a bracket 42 secured to one of the walls of the shed. The drum is fitted with a handle 43 for operating it, and the hand-lever travels over a segment 44 having holes 55 45 to receive a pin 46 carried by the hand-lever for locking the latter in adjusted position. The operating ropes 41 of the slides travel over suitably located guide-pulleys.

In feeding sheep from open troughs, the 60 tame sheep will crowd around and frequently

knock the feed from the hands of the attendant, so that it will be impossible to distribute the feed evenly; also the wild sheep will stay away from the rack until the attendant has left the same, and by that time the tame 70 sheep will have eaten most of the feed. With the apparatus herein described the objections noted above are entirely overcome. The attendant with one motion of the hand-lever 32 throws the covers back against the 75 rack-bars to shut out the sheep, and then proceeds to distribute the grain in the feed-troughs. After this is done the sheep are called, and when they are all in their proper places, and evenly distributed, the covers are 80 swung away from the rack-bars so that the animals may have access to the troughs. After the grain has been consumed, the slides 39 are dropped to again shut out the animals. The feed-trough covers are then closed, and 85 hay or shredded fodder is thrown on top thereof, after which the slides are raised and the animals again have access to the feed.

A rack having feed-troughs provided with covers as herein described can be employed 90 for feeding grain, and also hay or shredded fodder. The slides 39 may be left off as the sheep on the outside cannot interfere with the proper distribution of the hay or fodder; but by using the slides, chaff and dirt will be 95 kept out of the wool of the heads and necks of the animals. For racks having no feed-troughs, and designed to feed hay or shredded fodder only, the slides only will be employed.

The apparatus herein described is simple 100 in construction, has no complicated parts to get out of order, it can be cheaply produced and easily operated, and it effectually serves the purpose for which it is designed.

While the particular arrangement of 105 troughs shown and described is most convenient, it will be understood that the apparatus can be readily applied to differently arranged troughs, as guide-pulleys can be employed to carry the operating-ropes in any 110 direction.

I claim:

1. In a feed-rack, the combination of a feed-trough located adjacent the rack-bars on one side thereof, a cover having a hinge 115 connection with the trough at opposite sides thereof, and means connected to the cover for swinging it open from one of said sides to cover the rack-bars, and from the other side to uncover the trough.

2. In a feed-rack, the combination of a feed-trough located adjacent the rack-bars on one side thereof, a cover having a hinge connection with the trough at opposite sides thereof, means connected to the cover for 125 swinging it open from one of said sides to cover the rack-bars, and from the other side to uncover the trough, a slide for covering the rack-bars when the trough is closed, and means for operating the slide.

3. In a feed-rack, the combination of a feed-trough located adjacent the rack-bars on one side thereof, a cover, a hinge connection between the cover and the trough comprising rods, one of which is connected at its ends to the front edge of the cover and to the rear side of the trough, respectively, and the other rod being connected at its ends to the rear edge of the cover and to the front side of the trough, respectively, and means connected to the cover for swinging it open from either side of the trough. 10

In testimony whereof I affix my signature, in presence of two witnesses.

SIDNEY F. MOORE.
